U. PIAGNERI

CIGARETTE HOLDER

Filed Aug. 15, 1922

UNITED STATES PATENT OFFICE.

UMBERTO PIAGNERI, OF SAN FRANCISCO, CALIFORNIA.

CIGARETTE HOLDER.

Application filed August 15, 1922. Serial No. 581,946.

To all whom it may concern:

Be it known that I, UMBERTO PIAGNERI, a subject of the King of Italy, residing at the city and county of San Francisco and 5 State of California, have invented new and useful Improvements in Cigarette Holders, of which the following is a specification.

This invention relates to cigarette holders.

10 It is the object of the present invention to provide an improved form of cigarette holder which is susceptible of manipulation to grip and retain a cigarette in a correct position, and to quickly release and 15 eject the cigarette when desired.

The invention contemplates the provision of a cigar or cigarette holder having gripping members arranged adjacent the socket of the holder and means for manipulating the same whereby they may be separated and projected from the socket for releasing and ejecting a partially consumed cigarette, or for receiving the end of an unsmoked cigarette, after which the gripping members 25 may be caused to grip the cigarette, and be drawn inwardly to a concealed position within the socket of the holder.

One form which the invention may assume is exemplified in the following description and illustrated by way of example in the accompanying drawings, in which:

Fig. 1 is a view in plan disclosing the preferred embodiment of the invention.

35 Fig. 2 is a similar view showing the cigarette gripping members in extended position for the reception or discharging of a cigarette.

Fig. 3 is a view in plan section showing 40 details of construction.

Fig. 4 is a side elevation with parts in section to show certain details of construction.

Referring more particularly to the drawings, 10 indicates a cigarette holder provided with a mouth piece 11 and a stem 12, which are connected by a threaded joint 13. The stem 12 in the present instance is formed in two sections, 14 and 15, which 45 are separably connected by a threaded joint 16. The section 15 of the stem is formed with a cigarette receiving socket 17, which is in communication with a central bore 18 in the mouthpiece, through a passage- 50 way 19 and filtering chamber 20. The filtering chamber, as shown in Fig. 3, is

located in an enlarged bore formed in the stem section 14, and is enclosed by a perforated shell 21. This shell is adapted to contain absorbent material for preventing nicotine from being drawn through the mouthpiece with the smoke, into the smoker's mouth, and in some instances to contain a medicament or disinfectant. The shell 21 is detachably connected at one end, to a shoulder 22 formed on a shank 23 which is a reduced continuation of the stem section 15. The shank 23 projects into the shell 21 and is slotted as at 24 to permit smoke drawn through the stem to freely circulate through the absorbent material for the purpose described. A trap is also formed to prevent saliva from passing into the stem and reaching the tobacco.

Formed in opposite sides of the stem section 15 is a pair of cam grooves 25, mounted in which is a pair of arms 26 which are formed with a cam face corresponding in contour to that of the grooves. The arms 26 each support a segmental gripping jaw 26^a at their outer end for gripping the end of a cigarette. It can be readily understood by referring to Fig. 3, that as the arms are moved outwardly, the co-operating cam surfaces mentioned will positively cause the end of the arms carrying gripping jaws to spread. Likewise, when the arms are drawn inwardly the gripping jaws will be positively closed and will nest within the socket 17. The gripping jaws are 80 of a curvature that they will readily grip cigarettes of various diameters and securely retain them in correct position with their ends within the socket 17.

For manipulating the arms 26, a sleeve 95 member 27 is provided and is slidably mounted on the stem section 15. The sleeve is slotted at opposite sides as at 28 to accommodate the arms. These slots, however, are not continuous throughout the 100 length of the sleeve, but are interrupted by a solid portion 19 which fits into a recess 30 formed in the outer edge of each arm. This connects the arms and the sleeve so that movement imparted to the latter will 105 be transmitted to the arms. The inward movement of the arms is limited as the arms will wedge between the sleeve and the stem.

Secured at the outer end of the stem section 15 is a band 31, which is grooved to accommodate and guide the arms 26. The

central bore of this band is slightly enlarged at its inner end to permit movement of the sleeve 27. The depth of the bore is such as to limit the outward movement 5 of the sleeve as the end of the latter will engage the shoulder 32 in the band when the gripper arms have been sufficiently extended and spread.

In operation of the invention, the various 10 parts of the device are constructed and assembled as shown in the drawings. The sleeve 27 may then be moved forwardly to extend and spread the gripping jaws 26. The end of a cigarette may then be interposed between the jaws and the sleeve 27 manipulated to draw the jaws inwardly to grip the cigarette and retain the end thereof firmly within the socket 17 of the stem. It is understood that smoke drawn through 15 the stem will be thoroughly filtered in the chamber 20 before it can escape to the mouthpiece 11.

When the cigarette has been sufficiently consumed, the sleeve may again be manipulated to extend and spread the gripping jaws to release and eject the stub. 20

It is obvious from the drawings that the device may be easily and quickly taken apart for cleaning purposes, or for replacing the absorbent material in the filtering 25 chamber.

While I have shown the preferred form 30 of my invention, it is understood that various changes in form, proportion, combination and arrangement of parts may be made without departing from the spirit of the invention.

Having thus described my invention, what I claim and desire to secure by Letters 40 Patent is:

1. A cigarette holder formed with a mouthpiece and a stem, the latter having a cigarette receiving socket formed therein, a plurality of gripping jaws adapted to nest within said socket, an arm connected to each jaw and extending parallel to the stem, and co-operating cam surfaces on the arms and stem whereby the arms may be manipulated to positively open and close 50 the jaws.

2. A cigarette holder comprising a mouthpiece and a stem, cam grooves formed in the periphery of the stem parallel to the longitudinal axis thereof, said stem having 55 a cigarette receiving socket, an arm in each

groove, a gripping jaw carried at the end of each arm and adapted to nest in said socket, means for moving the arms longitudinally in unison, and cam surfaces on the arms co-operating with the cam grooves 60 whereby the gripping jaws will open when the arms are moved in one direction, and close when the arms are moved in the other direction.

3. A cigarette holder comprising a mouth-piece and a stem, said stem having a cigarette receiving socket formed in one end thereof, cam grooves formed in the periphery of the stem parallel to the longitudinal axis thereof, an arm in each groove, 65 a gripping jaw carried by the end of each arm and adapted to nest in said socket, a sleeve slidably mounted on the stem and pivotally connected to said arms for moving the arms longitudinally in unison, said arms being formed with cam surfaces adapted to cooperate with the cam grooves whereby the gripping jaws at the ends of the arms will be spread when the arms are moved in one direction and be closed when 70 the arms are moved in the opposite direction.

4. A cigarette holder comprising a mouth-piece and a stem, said stem being formed in two threadedly connected sections, one 75 of said sections being reduced in diameter and having a socket formed in the end thereof, cam grooves formed in the periphery of said reduced section and extending parallel to the longitudinal axis thereof, an arm in each groove, a gripping jaw carried at the end of each arm and adapted to nest in said socket, a sleeve slidably mounted in said reduced section and pivotally connected to said arm, cam surfaces 80 on said arms adapted to cooperate with the cam grooves whereby the gripping jaws will be spread when the sleeve is moved in one direction and be closed when the sleeve is moved in the opposite direction, a band 85

100 fixed at the socket end of said reduced section, grooves in said band in alignment with the cam grooves in the stem section to guide the arms during movement of the sleeve, movement of said sleeve being limited 105 in one direction by said band and in the other direction by the enlarged portion of the stem.

UMBERTO PIAGNERI.
